UNITED STATES PATENT OFFICE.

GEORGE A. LONG, OF HARTFORD, CONNECTICUT, ASSIGNOR TO THE GRAY TELEPHONE PAY STATION COMPANY, OF HARTFORD, CONNECTICUT, A CORPORATION OF CONNECTICUT.

TELEPHONE TOLL APPARATUS.

No. 815,107.

Specification of Letters Patent.

Patented March 13, 1906.

Application filed March 11, 1903. Serial No. 147,260.

To all whom it may concern:

Be it known that I, GEORGE A. LONG, a citizen of the United States, and a resident of Hartford, in the county of Hartford and State of Connecticut, have invented certain new and useful Improvements in Telephone Toll Apparatus, of which the following is a specification.

The object of my invention is to provide a toll-collecting apparatus which may be used in connection with "automatic" telephone systems. A form of device by the use of which this object may be attained is illustrated in the accompanying drawings, in

15 which—
Figure 1 is a view in front elevation of a telephone set embodying the automatic system and showing my toll-collecting device applied thereto. Fig. 2 is a view in section 20 through the casing containing the toll-collecting devices with the parts in normal position of rest and showing a coin as it first engages the parts. Fig. 3 is a like view showing the parts in position for use of the telephone and with a coin in position just before 25 it is released from the plunger. Fig. 4 is a view in section through a portion of the lower part of the casing, showing the mechanism for releasing the coin by the pressure of the 30 call-button.

The automatic telephone system, as is well known to those familiar with the art, is automatic in the sense that each subscriber may make connection with any other subscriber by the manipulation of the mechanism at his own instrument, thus obviating the necessity of having central operators to make connections.

Such a telephone instrument as illustrated 40 in the drawings comprises a box 1, containing the telephone instrument having call-bells 2, a transmitter 3, a receiver 4, a switch-lever 5, and a connection-dial 6. A subscriber wishing to call a certain number manipulates the connection-dial 6 to connect his instrument with the line in which the other instrument is connected. This being done, he can tell by placing the receiver to his ear whether or not that line is in use. If he finds 45 it is not in use, he presses the call-button 7, which rings the bells at the instrument being called. If the line is in use, the receiver is returned to the switch-lever.

In adapting a toll-collecting apparatus for use with automatic systems it is essential that it be of such form as to be readily applied without requiring any special construction or arrangement of the telephone instrument that the requirement imposed for the use of the instrument shall be complied with before such use can be had. Assuming that this requirement is the depositing of a token or coin, it is necessary to provide for the return of the coin to the user in case the desired connection cannot be had. If the telephone is used, then there must be provided a means for allowing the coin or token to be finally deposited in a suitable collecting draw or pocket provided for the purpose. Inasmuch as there is no central operator to perform any of the acts necessary to accomplish the above results, it is necessary that the construction of the apparatus shall be such as to do so incidental to the use of the telephone instrument.

In constructing an apparatus which will fulfil all of the requirements of the case I provide a casing 8, attached to the instrument, so that the switch-lever passes through a slot 13 in it, which is of sufficient length to permit the necessary movement of the lever. 75 When the instrument is not in use, in which case the parts occupy what may be termed their "normal" positions, the receiver is carried by the switch-lever, which is in its lowest position. One leg 17 of a slotted locking-lever 14, which is pivoted in the casing 8, closes 80 the slot 13 in the casing, and its lower end overlies the switch-lever, locking it against upward movement even though the receiver be removed. The other leg 18 of the locking-lever 14 projects into a coin channel or guide 90 10 in the casing. Projecting into the coin-channel 10 opposite to the leg 18 is a plunger 12, connected with a push-button 11, which is outside the casing and held in position by a 95 spring 36, so that the distance between the plunger and the leg 18 is such as to retain a coin when it drops down the guide 10. A slot 26 through the casing communicates with the coin-guide. A spring 25 holds the locking-lever 14 in its normal position with the leg 18 in the coin-guide and the leg 17 covering the slot 13 and overlying the switch-lever 5. This position of the parts is seen in Fig. 2. Let a coin be dropped into the channel 10, where it will assume a position be-

tween the plunger 12 and the leg 18. When the push-button is pressed in, the coin communicates the motion to the locking-lever 14, throwing it to the right to the position shown 5 in Fig. 3, where it is held in position by a latch-lever 34, pivoted in the casing and having a latch 33, which engages the catch 15 on the locking-lever 14. If the receiver is now removed from the hook, the switch-hook lever is free to move up to its highest point. The lower end of this latch-lever has a cam 35, which lies over the slot 13 in the path of movement of the switch-lever, as seen in Fig. 3. A spring 24 holds the latch-lever 34 in 10 operative position. Upon releasing the push-button 11 the spring 36 returns it and the plunger 12 to normal position and the coin is free to drop farther down the guide. This it does until it strikes against a detent 30, 15 which projects through a slot 31 in the plate 23, which forms a side of the channel, into the guide. This detent is carried by a lever 29, pivoted in the lower part of the casing and having its opposite end connected with the 20 call-button 7 in such manner that it is moved whenever the call - button is pressed, thus throwing the detent 30 to the left from the position in which it is seen in Figs. 2 and 3 and in which position it is normally held by 25 the spring 32. The parts being in the positions shown in Fig. 3, except the plunger and the coin, and assuming that the push-button 11 is released and the plunger retracted, allowing the coin to drop to the position shown 30 in dotted lines in this figure, the user, if he finds that the line is open, presses the call-button 7 to ring the bell at the other instrument. As has been seen, this pressure of the button 7 moves one end of the lever 29, 35 throwing the detent 30 to the left, and the coin, which has been rested between the detent and the rear wall of the channel, is released and falls through the coin-deposit outlet into the money-drawer 9, provided at the 40 lower end of the casing. However, if after pressing the push-button 11 and releasing the switch-hook lever 5 and dropping the coin onto the detent 30 the user finds that the line he wants is in use he hangs the 45 receiver on the switch-lever, causing it to move downwardly to its normal position. During this downward movement of the lever it strikes the cam 35 of the latch-lever 34 and disengages the latch 33 from the catch 15 on 50 the locking-lever 14 and the spring 25 draws the locking-lever 14 back to normal position. The locking-lever 14 carries a finger 20, projecting downwardly from the leg 18, as shown, and having an inturned end 21 working 55 in a slot 22 in the plate 23 at the point where the coin rests on the detent 30. The inturned end 21 moving quickly with the locking-lever 14 under the influence of the spring 25 strikes the coin and throws it over 60 the detent 30 out of the coin-return outlet 27

into the clip 28, where it may be recovered by the user.

To briefly describe the complete operation of the apparatus, the user first deposits the coin, which falls to rest between the plunger 12 and leg 18 of the locking-lever 14. He then presses the push-button 11, throwing the locking-lever to the right, releasing the switch-lever, so that it rises to the position shown in Fig. 3, the latch 33 engaging the catch 15 to hold the locking-lever in this position. The push-button is released and the plunger retracted, allowing the coin to drop onto the detent 30. The connection-dial is now manipulated, and when the proper connection is made the user can tell by placing the receiver to his ear whether or not the desired wire is busy. If the wire is open, the call-button 7 is pressed, throwing the detent out of the way of the coin and allowing it to fall into the box. If the wire is busy, the receiver is hung on the switch-lever, drawing it down, during which movement it disengages the latch 33 from the catch 15, and the spring quickly returns the locking-lever to its normal position, the end 21 of the finger 20 throwing the coin out into the clip 28.

It will thus be seen that in order to use my toll apparatus with automatic telephone instruments there are but two things the user must do in addition to what is essential to be done in order to use the instrument—one is the depositing of the coin and the other is the pressing of the push-button. All the other things necessary to be done, either depositing the coin finally or returning it to the user, are accomplished by the ordinary use of the instrument.

I claim as my invention—

1. In a telephone instrument including a receiver, a switch-lever and a transmitter, means for locking said lever in its lower position, a coin-channel appurtenant to said locking means, a plunger extending into said coin-channel and adapted to actuate said locking means through the medium of a coin to unlock said lever, a device for arresting the coin as it drops after the said lever is released, a call - button operative by the calling subscriber to notify the called party, and operative connections between said call-button and said arresting device whereby the operation of the former will move the latter to release and deposit the coin.

2. In a telephone toll apparatus the combination with a telephone instrument including a receiver, a transmitter, a switch-lever, a connection-dial and a signaling device under the control of the calling subscriber whereby the calling subscriber can make his own connection with the line desired and make the particular call desired on that line by means of the signaling device, of means for collecting a toll for the use of said instrument, said means including a casing having

a coin-channel; means having a part projecting into said casing, for locking said switch-lever in its low position; means for unlocking said lever through the medium of a coin; a 5 device for arresting said coin as it drops after said lever is released; means connected with and operated by the signaling device for depositing the coin; and means controlled by the switch-lever for returning the coin when 10 the signaling device is not operated, substantially as described.

3. In a telephone toll apparatus the combination with the instrument which includes a receiver, a switch-lever and a transmitter, a 15 coin-channel having a coin-return and coin-depositing outlet, locking means for said lever projecting into said channel, a plunger projecting into the channel opposite said lever and forming therewith an obstruction to 20 receive and hold a coin which forms an operative connection between said plunger and said locking means whereby on the operation of said plunger said switch-lever is unlocked, means actuated by said switch-lever for 25 passing the coin through the return-outlet when the instrument is not used, a call-button and means connected therewith and actuated thereby for passing the coin through the delivery-outlet when the instrument is 30 used, substantially as described.

4. In a telephone toll apparatus for use with automatic telephone instruments, the combination with said instrument which includes a receiver, a switch-lever normally 35 locked, a transmitter, a signaling device, and a connection-dial, of a casing through which said switch-lever extends, a coin-channel therein having a coin-depositing outlet, means for unlocking said lever through the 40 medium of a coin, a detent projecting into said channel above said outlet and adapted to arrest said coin after said lever is unlocked, and operative connections between said detent and the signaling device whereby upon 45 operation of the latter the detent is moved to open said coin-depositing outlet.

5. In a telephone toll apparatus for use with automatic telephone instruments, the combination with said instrument which includes a receiver, a switch-lever normally 50 locked, a transmitter, a signaling device, and a connection-dial, of a casing, through which said switch-lever extends and means for unlocking said lever through the medium of a coin, a coin-channel therein, return and deposit outlets at the lower end of said coin-channel, a detent projecting into said channel above said return and deposit outlets, operative connections between said detent and the 55 signaling device whereby upon the operation of the latter the detent is moved to open said deposit-outlet, and mechanism mounted in the casing and controlled by the switch-lever for moving the coin to the return-outlet.

65 6. In combination with a telephone set in-

cluding a switch-lever and a signaling device both controlled at the same instrument, a coin-channel having a coin-return and coin-depositing outlet, means for retaining the coin in the channel, means for controlling the 70 movement of the switch-lever adapted to guide the coin out of the coin-return outlet, and means connected with the signaling device for passing the coin through the depositing-outlet when the signal is actuated. 75

7. In combination with a telephone set including a switch-lever and a signaling device both controlled at the same instrument, a coin-channel having a coin-return and a coin-depositing outlet, a detent for retaining the 80 coin in the channel, means actuated by the switch-lever for forcing the coin over the detent into the coin-return outlet, and means connected with and operated by the signaling device for removing the detent whereby the 85 coin is allowed to pass through the depositing-outlet.

8. In combination with a telephone set including a switch-lever and a signaling device adapted to be manipulated by the operator 90 at the same instrument, a coin-channel, a detent connected with the signaling device and adapted to be removed from the path of the coin when said signaling device is actuated, and means connected with the switch-lever 95 for forcing the coin over the detent when said lever is released to assume its normal position.

9. In combination in a telephone set including a switch-lever and a signaling device 100 and means for selecting a call-number, all under the control of the calling subscriber, a self-contained toll-collecting apparatus adapted to be applied to said instrument and provided with a lock normally engaging 105 and locking the switch-lever, a coin-channel operatively arranged with reference to said lever, means for unlocking the lever through the medium of the coin, a coin-returning outlet and a coin-depositing outlet appurtenant 110 to the coin-channel, a detent arranged to stop the coin adjacent to said outlets, and a connection intermediate the detent and the signaling device whereby the former is actuated by the movement of the latter, and means 115 for discharging the coin into the return-outlet when the signaling device is not operated.

10. In combination with a telephone set including a switch-lever and a signaling device controlled by the calling subscriber, a self-contained toll-collecting apparatus adapted 120 to be applied to said telephone set, a lock located therein and normally engaging and locking the switch-lever, a coin-channel, a coin-returning and a coin-depositing outlet 125 operatively arranged with reference to said channel, means operated by said lock for moving the coin transversely of the channel, and means connected with the signaling device for passing the coin through the coin-de- 130

positing outlet when the signaling device is actuated.

11. The combination with a telephone set including a switch-lever, a signaling device and a connection-dial, of a lock therefor, a coin-channel, a plunger projecting into said channel and adapted to actuate said lock through the medium of a coin to unlock the lever, a coin-return and a coin-depositing outlet located appurtenant to said coin-channel, means for holding the lock disengaged from the switch-lever, coin-retaining means located in the channel above the return and depositing outlets and operatively connected with the signaling device for depositing the coin in the money-drawer when said signal device is actuated, said holding means coöperating with the switch-lever to engage the lock and the lever on the subsequent movement of the latter, and means carried by said lock for moving the coin into the return-outlet when the desired connection is not obtained.

12. In combination with a telephone set including a switch-lever and a signaling device controlled by the calling subscriber, a self-contained toll-collecting apparatus adapted to be applied to said telephone set and comprising a lock normally engaging and locking the switch-lever, a coin-channel, coin-return and coin-depositing outlets operatively arranged with reference to said channel, means for disengaging said lock from said lever, means connected with the signaling device for passing the money through coin-depositing outlet when the signal device is actuated, and means appurtenant to the switch-lever and controlled thereby for throwing the coin into the coin-return outlet when the switch-lever is returned to locked position.

13. In combination with a telephone including a switch-lever and a signaling device, both arranged to be actuated from the same instrument, a coin-channel, a plunger projecting into the channel, a lock for the switch-lever, means for holding the lock disengaged from the switch-lever, said holding means co-operating with the switch-lever to release it from an engaging position with reference to the lock, a retaining device operatively connected with the signaling device and actuated thereby for controlling one movement of a coin deposited in the coin-channel, and an ejector connected with the lock and adapted to affect a second movement of the coin when the signal device has not been operated.

14. In combination with a telephone including a switch-lever and a signaling device, a coin-channel, a plunger projecting into the channel, a swinging lock normally interposed in the path of movement of the switch-lever, a leg on said lock co-operating with said plunger through the medium of a coin to unlock said switch-lever, a latch to engage the lock located in the path of movement of the switch-

lever, and a detent located in the coin-channel, and adapted to arrest the coin after the switch-lever is unlocked, said detent being connected with the signaling device.

15. In combination with a telephone including a switch-lever, a signaling device and means for selecting a call connection, a self-contained toll-collecting apparatus including a coin-channel ending in coin-returning and coin-depositing outlets, a detent arranged in the channel above said outlets, and connected with the signaling device whereby upon the operation of said signaling device said detent is moved to permit the coin to pass through the depositing-outlet, a lock normally interposed in the path of movement of the switch-lever, means for actuating said lock including the coin, said actuating means arranged to vary the position of the coin with reference to the coin-returning and coin-depositing outlets whereby said coin will fall against the detent, and means connected with the lock for throwing the coin from the detent into the coin-returning outlet when said lock assumes a normal locking position with reference to the switch-lever.

16. In combination with a telephone including a switch-lever and a signaling device, a coin-channel, a detent located in the coin-channel and connected with the signaling device, a lock normally interposed in the path of movement of the switch-lever, a finger secured to the lock to engage a coin located on the detent, means for exerting force on the lock, and a latch for holding the lock disengaged from the switch-lever and operated by the latter in its movement.

17. In combination with a telephone instrument including a switch-lever, a signaling device and means for selecting a call connection, a self-contained toll-collecting apparatus adapted to be applied to said instrument and with the switch-lever passing therethrough, a coin-channel arranged in said toll-collecting apparatus, a lock for said switch-lever and releasing means therefor actuated through the medium of a coin, means for holding said lock out of engagement with said switch-lever, said means being actuated by the switch-lever to release said lock, a coin-returning and a coin-depositing outlet, a detent operatively arranged with reference to said outlet and adapted to retain a coin, and a connection extending from said detent and connected with the signal-actuating device whereby the coin is released and passed to the depositing-outlet when the signal device is actuated, and means carried by said lock for throwing the coin out of the return-outlet when the signal device is not actuated.

18. In combination with a telephone instrument including a switch-lever, a signal device and means for selecting a call connection, a self-contained toll-collecting apparatus adapted to be applied to said instrument

and with the switch-lever passing therethrough, a coin-channel arranged in said toll-collecting apparatus, a lock for said switch-lever and releasing means therefor, actuated through the medium of a coin, means for holding said lock out of engagement with said switch-lever, said means being actuated by the switch-lever to release said lock, a coin-returning outlet and a deposit-outlet, a detent operatively arranged with reference to said outlets and adapted to retain a coin, a connection extending from said detent and connected with the signal device whereby the coin is released and passed to the money-drawer outlet when the signal device is actuated, and an ejector operatively connected with the lock and controlled in its movement by the switch-lever whereby the coin is passed through the coin-returning outlet whenever the signaling device is not actuated.

19. In combination with a telephone in-

cluding a switch-lever, a signaling device and a call-wire-selecting apparatus, all actuated at the same instrument, a bodily-removable 25 and complete toll-collecting apparatus arranged to be applied to the side of said instrument with the switch-lever projecting therethrough, a coin-channel arranged in said toll-collecting apparatus and having a coin-returning outlet and a coin-depositing outlet, a plunger and a lock projecting into said channel and adapted to be connected through the medium of the coin, said lock normally locking the switch-lever, means operated by the signaling device for directing the coin to the coin-depositing outlet, and means controlled by the switch-lever for directing the coin to the return-outlet when the signaling device is not operated.
